(57) **CLAIM**

The ornamental design for a cable organizer, as shown and described.

DESCRIPTION

FIG. 1 is a front perspective view of a cable organizer showing, in particular, the ornamental design thereof;

FIG. 2 is a top plan view of the cable organizer of FIG. 1;

FIG. 3 is a bottom plan view of the cable organizer of FIG. 1;

FIG. 4 is a left side elevation view of the cable organizer of FIG. 1. It will be understood that a right side elevation view will be a mirror image of the left side elevation view; and, FIG. 5 is a front end view of the cable organizer of FIG. 1. It will be understood that a rear end view will be a mirror image of the front end view.

The broken lines in the drawings represent the boundaries of the claimed design. The broken lines form no part of the claimed design.
